US00D817741S

(12) **United States Design Patent** (10) **Patent No.:** **US D817,741 S**
West (45) **Date of Patent:** **** May 15, 2018**

(54) **LEVELING FOOT**

(71) Applicant: **SolarCity Corporation**, San Mateo, CA (US)

(72) Inventor: **Jack Raymond West**, San Rafael, CA (US)

(73) Assignee: **SolarCity Corporation**, San Mateo, CA (US)

(**) Term: **15 Years**

(21) Appl. No.: **29/567,387**

(22) Filed: **Jun. 8, 2016**

Related U.S. Application Data

(63) Continuation of application No. 29/521,138, filed on Mar. 20, 2015, now Pat. No. Des. 759,464, which is a continuation of application No. 13/402,846, filed on Feb. 22, 2012, now abandoned, which is a continuation-in-part of application No. 12/830,249, filed on Jul. 2, 2010, now Pat. No. 8,919,052, said application No. 29/521,138 is a continuation of application No. 14/504,168, filed on Oct. 1, 2014, now Pat. No. 9,599,280, which is a continuation of application No. 13/402,846, filed on Feb. 22, 2012, now abandoned, which is a continuation-in-part of application No. 12/830,249, filed on Jul. 2, 2010, now Pat. No. 8,919,052, said application No. 29/521,138 is a continuation of application No. 14/454,471, filed (Continued)

CLAIM

The ornamental design for a leveling foot, as shown and described.

DESCRIPTION

FIG. 1 is a top front perspective view of a leveling foot showing the claimed design;

FIG. 2 is a top rear perspective view thereof;

FIG. 3 is a left side view thereof;

FIG. 4 is a right side view thereof;

FIG. 5 is a front view thereof;

FIG. 6 is a rear view thereof; and,

FIG. 7 is a top view thereof.

The dashed broken lines in the figures show portions of the leveling foot that form no part of the claimed design.

The dot-dash broken lines in the figures show boundaries that form no part of the claimed design.

1 Claim, 7 Drawing Sheets

Related U.S. Application Data

on Aug. 7, 2014, now Pat. No. 9,518,596, which is a continuation-in-part of application No. 12/830,249, filed on Jul. 2, 2010, now Pat. No. 8,919,052, said application No. 29/521,138 is a continuation of application No. 14/531,155, filed on Nov. 3, 2014, which is a continuation of application No. 12/830,249, filed on Jul. 2, 2010, now Pat. No. 8,919,052.
